COMBINATION TRAVELING BLOCK AND SWIVEL CONNECTION

Byron C. Christensen, Oklahoma City, Okla.

Application July 31, 1946, Serial No. 687,312

8 Claims. (Cl. 254—195)

1

This invention relates to traveling blocks and particularly to a combination traveling block and swivel connection adapted for use in the tackle of a rotary drilling rig or the like for handling strings of drill pipe, casing and similar heavy loads.

The ordinary traveling block and its connection with the bail of a swivel head or elevator is of considerable combined length so that it limits the ultimate height that the drill pipe or other load can be raised within the derrick of a drilling rig without danger of colliding the traveling block with the crown pulley of the derrick. It is often desirable to obtain a maximum lift but with the high speed operation of the drawworks it is difficult for the driller to accurately judge the position of the traveling block as it approaches the crown block of the derrick. Consequently, to avoid accidents, it is impossible to utilize the effective height of a given derrick. This is particularly objectionable in portable drilling rigs where the height of the derrick must be kept within the length limits that can be transported over public highways.

Therefore, the principal objects of the present invention are to provide a combined traveling block and swivel connection that is characterized by its extremely short, compact construction; to provide a substantially sturdy traveling block unit of small size and capable of handling heavy loads; to provide a traveling block with shock absorbing means located intermediate the block sheaves; to provide an improved mounting of the sheaves in the body of a traveling block structure; to provide a traveling block structure having a fewer number of parts and connections to be made when the block is assembled in a tackle mechanism; and to provide a sheave arrangement that assures a centralized draft through the axis of the traveling block.

In accomplishing these and other objects of the invention, I have provided improved structure, the preferred form of which is illustrated in the accompanying drawing wherein:

Fig. 1 is a side elevational view of my improved traveling block and swivel connection member and showing a part of the block body broken away and in section to better illustrate the swivel bushing and lock therefor.

Fig. 2 is a longitudinal central section on the line 2—2 of Fig. 1.

Fig. 3 is a cross section on the line 3—3 of Fig. 2. Referring more in detail to the drawing:

1 designates a combined traveling block and swivel connection constructed in accordance with the present invention and which includes a traveling block body 2. The body 2 is constructed in a

2

single piece having a streamlined shape and a substantially smooth exterior to avoid possibility of the block "hanging up" on a part of the derrick or the like when the tackle is in operation. The body of the block includes an upper portion 3 of substantially semi-cylindrical shape with the axis extending horizontally of the longitudinal axis of the body of the block and a lower portion 4 having converging sides 5 and 6 extending downwardly from the rounding top 7. The other sides 8 and 9 are preferably rounded from the lower end of the block to the ends of the semi-cylindrical portion 3 as best shown in Fig. 2. Formed within the body of the block coaxially with the longitudinal axis thereof is a sleeve-like partition 10 forming a central compartment 11 opening through a boss 12 at the top of the block (Fig. 1) and terminating within the lower end of the block in an annular bearing seat 13 encircling an opening 14 in which is rotatably mounted a swivel bushing 15 having an annular flange 16 supported upon an anti-friction bearing 17 carried on the seat 13. The upper end of the bushing and the upper face of the flange 16 provide a support for one end 18 of a coil spring 19 later described. The opposite end of the bushing projects through the opening 14 and is encircled with an oil sealing ring 20 for retaining the lubricant for the bearing 17. The bushing is provided with an axial opening 21 preferably of polygonal shaped cross section to slidably and non-rotatably mount a stem 22 of a connecting member 23 which in the illustrated instance is shown as being a safety hook although the stem may be provided with a clevis or other connecting device without departing from the spirit of the invention.

The polygonal-shaped portion of the stem terminates substantially midway of the block in a cylindrical extension 24 having threads 25 for mounting an adjusting nut 26 on the stem and providing a stop face 27 adapted to engage a stop face 28 on the swivel bushing when the spring 19 is compressed under load. The nut 26 includes a sleeve-like body of substantial length having a threaded bore 29 to receive the threaded end of the stem and is provided with an annular flange 30 spaced from the upper end to form an annular seat for a thrust bearing 31, the bearing being retained on the seat by a washer 32 sleeved on the threaded stem and secured by a nut 33 and a cotter pin 34 extending through the nut and stem as shown in Fig. 2.

The upper end of the compartment 11 is closed by a cap 35 that is seated on the boss 12 and has a depending annular flange 36 extending into the

compartment and into a position to be engaged by the thrust bearing. The spring 19 is coiled about the stem and has its upper end bearing against the flange 30 so as to normally support the thrust bearing in contact with the annular flange 36 when the load carried by the connection member is relatively light or has been removed from the block. The cap 35 is secured by fastening devices 37 and has an eye 38 projecting therefrom. At times it may be desirable to lock the bushing from rotation and this is effected by providing a latch 39 that is pivotally mounted on a cross shaft 40 journalled in opposite side walls of a lateral recess 41 adjacent the flange of the bushing. The latch 37 has a rounded end 42 adapted to be moved into position for engaging one or a series of notches 43 that extend transversely of the flange 16 as best shown in Fig. 1. The shaft 40 is actuated to move the latch into and out of engaging position by a hand lever 44 fixed to a projecting end of the shaft 40 as shown in Fig. 3.

Formed within the body of the block on opposite sides of the compartment 11 are sheave compartments 45 and 46 that open through the sides 5 and 6 to permit insertion of sheaves 47 and 48. The side walls 8 and 9 of the body of the block are provided concentric with the axis of the upper portion 3 with openings 49 and 50 which register with smaller openings 51 and 52 in the side walls of the tubular partition 10. The openings 49 and 50 are encircled on the outer sides of the body of the block by annular recesses 53 and 54 as shown in Fig. 2 for mounting spindles 55 and 56. The spindles 55 and 56 each include a stub shaft 57 of a diameter to snugly engage in the openings 51 and 52 and which are mounted on plates 58 that have portions 59 snugly engaged within openings 49 and 50. The plates are anchored in the recesses 53 and 54 by fastening devices such as cap screws 60. Mounted on the stub shafts are anti-friction bearings 61 carrying the hubs 62 of the respective sheaves as shown in Fig. 2. The sheave compartments 45 and 46 are closed on the respective sides 5 and 6 of the block by plates 63 and 64 secured in position by suitable fastening devices such as screws 65. The cover plates have openings 66 therein to facilitate threading of the tackle cable 67 and to facilitate threading thereof about the sheaves.

In assembling the traveling block the swivel bushing 16 and thrust bearing 17 are moved into the cylindrical compartment 11 through the open upper end thereof. The stem 22 of the hook is then moved through the opening 21 of the bushing so that the threaded end is located in the opposite end of the cylindrical chamber and inlapping relation with the sheave compartments. The spring 19 is then passed into the compartment 11 and over the stem 22 so that the end 28 seats upon the swivel bushing 16. The nut 28 is then passed over the upper end of the stem and turned to engage the threads for moving the flange 30 into contact with the upper end of the spring, the nut being turned on the stem until the stem projects from the upper end of the nut for mounting the retaining nut 33.

The thrust bearing 31 is then applied to the nut followed by the washer 32 and retaining nut 33. The cap 35 is applied to close the open upper end of the compartment 11 and form a stop for the thrust bearing 31. The sheaves 47 and 48 are moved into position through the open sides

of the compartments 45 and 46 so that the hubs thereof register with the openings 49.

The spindles 55 and 56 carrying the roller bearings are then moved into position through the bearings and into the openings 51 and 52. The cap screws 60 are applied to retain the spindles in position. The cover plates 63 and 64 are applied to complete the assembly.

The block is used in customary manner by threading the tackle cable 67 through the openings 66 and around the sheaves and the hook 23 is attached to the bail of the apparatus to be handled by the tackle.

When power is applied to the cable 67 and a load is depending from the hook 23, the spring 19 yields to reduce shock incidental to sudden application of power. If the latch 39 is in position shown in Fig. 1, the hook and swivel bushing are free to swivel within the body of the block to avoid twisting of the cable lines when the load is rotated; for example, as when unscrewing the joints of a drill pipe.

From the foregoing it is obvious that I have provided a tackle block assembly including a connecting member that is of compact construction, of streamlined shape, and composed of a comparatively small number of parts.

What I claim and desire to secure by Letters Patent is:

1. In a device of the character described including a body member having a central compartment extending through ends of the body member, a connecting member, a stem on the connecting member projecting into the compartment through one end and terminating at the opposite end of the body member, a swivel bushing for mounting the stem slidably in one end of the compartment, a spring sleeved on the stem and having one end seated on said bushing, a spring adjusting member mounted on the stem for engaging the opposite end of said spring, a thrust bearing carried by said adjusting member to move with the stem, and a cap closing the other end of the compartment and having a stop adapted to seat said bearing against action of said spring.

2. In a device of the character described including a body member having a central compartment extending through ends of the body member, a connecting member, a stem on the connecting member projecting into the compartment through one end and terminating at the opposite end of the body member, a swivel bushing swivelly supported at said open end of the compartment and having an axial bore, said bore and a portion of the stem being of a cross sectional shape to provide a non-rotative sliding connection between the stem and bushing through said portion of the stem a spring sleeved on the stem and having one end seated on said bushing, a spring adjusting member mounted on the stem for engaging the opposite end of said spring, a thrust bearing carried by said adjusting member, and a cap closing the other end of the compartment and having a stop adapted to engage and seat said bearing against action of said spring, said adjusting member having a sleeve portion terminating at substantially the upper terminal of said portion of the stem for forming a stop adapted to engage the swivel bushing to limit compression of the spring when a load is applied to the connecting member for support by said device.

3. A device of the character described including a body member having a central compartment

ment extending through one end of the body member, a connecting member, a stem on the connecting member projecting into the central compartment through said open end and terminating at the opposite end of the body member, a swivel bushing swivelly supported in said open end of the central compartment and having an axial bore, said bore and a portion of the stem having a polygonal cross section to provide a non-rotative slidable connection between said stem and bushing a spring sleeved on the stem and having one end seated within the body member, a spring adjusting member mounted on the stem for engaging the opposite end of said spring, a thrust bearing carried by said adjusting member to move axially in the body member with said stem, and a stop adapted to support said bearing against action of said spring in the expanding direction of the spring, said adjusting member having a sleeve portion terminating at said polygonal portion of the stem for forming a stop adapted to engage the swivel bushing to limit compression of the spring when a load is applied to the connecting member for support by said device.

4. A traveling block including a body member having sheave compartments on opposite sides of an intermediate compartment extending through one end of the body member with partitions dividing the compartments and cooperating with sides of the body member for forming sides of the sheave compartments, spindles arranged transversely of the sheave compartments and having support in the sides of the body member and said partitions, sheaves rotatable within the sheave compartment on the spindles, a swivel bushing, means rotatably mounting the swivel bushing in the end of the intermediate compartment opposite said sheaves, a cap closing the opposite end of the intermediate compartment and forming a stop directly between said sheaves, a stem having non-rotatable sliding support in said swivel bushing and terminating between said sheaves at said cap, a spring seat on the terminal end of the stem and having an annular shoulder, a thrust bearing carried on said shoulder and adapted to engage said stop on the cap, and a spring having one end seated on the swivel bushing and its other end engaging the spring seat to normally retain the thrust bearing in contact with said stop.

5. A traveling block including a body member having sheave compartments on opposite sides of an intermediate compartment extending through one end of the body member with partitions dividing the compartments and cooperating with sides of the body member to form sides of the sheave compartments, spindles arranged transversely of the sheave compartments, sheaves rotatable within the sheave compartments on the spindles, a swivel bushing, means rotatably mounting the swivel bushing in the end of the intermediate compartment opposite said sheaves, a cap closing the opposite end of the intermediate compartment and forming a stop directly between said sheaves, a stem having non-rotatable sliding support in said bushing and terminating between said sheaves at said cap, a spring seat on the terminal end of the stem and having an annular shoulder, a thrust bearing fixed to said shoulder and adapted to engage said stop on the cap, a spring having one end seated on the swivel bushing and its other end engaging the spring seat to normally retain the thrust bearing in contact with said stop, and a thrust bearing be-

tween the bushing sleeve and body member to cooperate with the thrust bearing on the spring seat for limiting expansion of said spring.

6. In a traveling block, a body member having sheave compartments on opposite sides of an intermediate compartment with partitions separating said compartments and cooperating with sides of the body member to form sides of the sheave compartments, said body member having recesses in the outer faces of said sides of the body member and having openings in the bottoms of said recesses registering coaxially with openings in the partitions, individual spindles extending through said openings, plate-like heads on the spindles and located in the recesses, and fastening devices for removably securing said heads to the body member.

7. In a traveling block, a body member having sheave compartments on opposite sides of an intermediate compartment with partitions separating said compartments and cooperating with sides of the body member to form sides of the sheave compartments, said body member having recesses in outer faces of said sides of the body member and having openings in the bottoms of said recesses registering coaxially with openings in the partitions, individual spindles extending through said openings, plate-like heads on the spindles and located in the recesses, fastening devices for removably securing said heads to the body member, sheaves rotatable on said spindles, said body member having sheave insert openings intermediate said sides of the sheave compartments for insertion of the sheaves, and plates for closing said insert openings.

8. A traveling block including, a body member having sheave compartments on opposite sides of an intermediate compartment extending through one end of the body member with partitions dividing the compartments and cooperating with sides of the body member for forming sides of the sheave compartments, spindles arranged transversely of the sheave compartments and having support in the sides of the body member and said partitions, sheaves rotatable within the sheave compartment on the spindles, a swivel bushing, means rotatably mounting the swivel bushing in the end of the intermediate compartment opposite said sheaves, a stem having non-rotatable sliding support in said swivel bushing and terminating between said sheaves, a spring seat on the terminal end of the stem and having an annular shoulder, a thrust bearing carried on said shoulder and adapted to engage a part on said body member, and a spring having one end seated on the swivel bushing and its other end engaging the spring seat to normally retain the thrust bearing in contact with said part.
